Nelson M. Howard

UNITED STATES PATENT OFFICE.

WILLIAM C. STEWART, OF SWAMPSMOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SEAM-POUNDING MACHINE.

1,346,275.

Specification of Letters Patent. Patented July 13, 1920.

Application filed May 11, 1916. Serial No. 96,786.

To all whom it may concern:

Be it known that I, WILLIAM C. STEWART, a subject of the King of England, residing at Swampscott, in the county of Essex and 5 State of Massachusetts, have invented certain Improvements in Seam-Pounding Machines, of which the following description, in connection with the accompanying drawings, is a specification, like reference characters on the drawings indicating like parts in the several figures.

This invention relates to machines for operating upon boots and shoes and is herein illustrated in connection with a machine for 15 pounding the seams, edges, backstays, etc., of the uppers of boots and shoes.

The machine of the present invention is an improvement upon the seam pressing machine shown in United States patent to 20 Bayley, No. 643455. When the patented machine is used on heavy stock a difficulty is sometimes experienced in introducing a piece of work between the hammer and anvil. For example it is in some cases desir- 25 able to pound the edges of the tops of shoes as a final operation preparatory to packing them. To perform this operation rapidly without opening the shoe, the operator holds the upper edges of the two quarters in alignment, pinching the upper as tightly as possible at the back seam, and presents the shoe, thus held, to the hammer so that the two edges and the fold or crease at the back seam are pounded at a single operation. 30 The general object of the present invention is to facilitate operating upon bulky work such as that which has been referred to above.

According to one feature of the present 40 invention a novel supporting member and an anvil having a common axis are provided with co-operating cam surfaces such that relative angular movement of the member and the anvil about the axis will raise 45 the anvil.

With this construction there is no difficulty in presenting a bulky piece of work between the hammer and anvil. At the same time the effective force of the blows of 50 the hammer can be controlled by holding the anvil at a given position so as to provide for work of different thickness.

This and other features of the invention

will be described in connection with an illustrative machine and pointed out in the ap- 55 pended claims.

Referring now to the accompanying drawing.

The figure is a side elevation partly in section of a machine in which the present 60 invention is embodied, a part of the frame having been broken away.

The frame 1, the oscillatory arm 3, the hammer 5, its mounting in the arm, and the means for continuously oscillating the arm 65 about the pivot 7 are similar to the corresponding elements of the machine of Patent No. 643455 and will not be described further.

Threaded into a split socket in the frame 70 underneath the hammer and held in adjusted position by a pinch-bolt 9 is an anvil supporting member herein shown as a sleeve 11 having a head upon which are formed a plurality of flat surfaces one of which 75 is shown at 111 and a plurality of inclined surfaces 211 leading up to said flat surfaces. The under side of the anvil is provided with similar flat and inclined surfaces as shown, so that angular movement of the anvil will 80 raise it to the position shown or permit it to descend. The anvil comprises a head 13 having a stem 15 which extends down through the sleeve 11, a cushioning washer 113 and a collar 213, the cam surfaces referred to above being formed on the under side of this last named member. A pin 17 connects the head 13, the washer 113 and the collar 213 so as to cause them to turn together. Fast to the lower end of the stem 90 15 is an arm 19 to the outer end of which is pivoted a link 21 adapted to be actuated through a bell crank lever 23 by a treadle rod 25 and treadle (not shown). A stop member 27 adjustably clamped to the link 95 21 is connected to the frame of the machine by a tension spring 29, the spring tending at all times to hold the member 27 against a bar 31 which forms part of the frame of the machine. The position of the stop mem- 100 ber 27 is such that the anvil is normally held in the raised position shown, with the flat surfaces on its under side in contact with the flat surfaces on the anvil supporting member 11.

In operation, power is applied to the ma-

chine to oscillate the hammer continuously. When a bulky piece of work such as the two top edges of the quarters is to be operated upon, the treadle is depressed, whereupon 5 the anvil by its own weight, descends as the inclined cam surfaces slide upon one another. This provides space between the anvil and hammer to permit presentation of the work, whereupon the treadle is released, 10 and the anvil rises under the influence of the spring 29. In some cases the anvil may rise at once to the position shown; in others the rise may not be completed until enough blows have been struck by the hammer to 15 flatten the work somewhat. It has been found in practice that when the inclined surfaces of the anvil and anvil support are in contact, an effective pounding may be given to the work, and consequently that the effective force of the blows of the hammer 20 may be controlled by holding the treadle, and thereby the anvil, in different positions.

Although the invention has been set forth in connection with a particular machine, it 25 should be understood that the invention is not limited in the scope of its application to the particular machine which has been shown and described.

Having thus described my invention what 30 I claim as new, and desire to secure by Letters Patent of the United States is:

1. A machine of the class described, having in combination, a hammer, an anvil supporting member rigid with the frame of the 35 machine, an anvil, said member and anvil having a common axis and being provided with coöperating cam surfaces such that relative angular movement of said anvil and member about said axis will raise said anvil 40 or permit it to be lowered, means for normally maintaining an angular relation between the anvil and member such that the anvil is held stationary in raised position and manually controlled means for varying 45 the angular relation at any time during the

operation of the machine to permit said anvil to be lowered.

2. A machine of the class described, having in combination a hammer, a supporting member rigid with the frame of the machine 50 located beneath the hammer and provided with raised flat surfaces and inclined surfaces leading up to and terminating in said flat surfaces, an anvil coöperating with said hammer and provided on its under side with 55 flat surfaces and inclined surfaces corresponding to those of the supporting member, means for normally holding said anvil and member in such angular position that the flat surfaces on said anvil and member are in engagement, and manually controlled means for producing relative angular movement between said anvil and supporting member at 60 any time during the operation of the machine to move said surfaces out of engagement so as to permit said anvil to be lowered.

3. A machine of the class described, having in combination a hammer, an anvil supporting sleeve threaded in the frame of the machine and having cam surfaces formed on 70 its upper end, an anvil having corresponding cam surfaces formed on its under side and provided with a stem extending through said sleeve, and means for turning said stem.

4. A machine of the class described, having in combination a hammer, an anvil supporting sleeve threaded in the frame of the machine and having cam surfaces formed on 75 its upper end, an anvil having corresponding cam surfaces formed on its under side and provided with a stem extending through said sleeve, an arm fast to the protruding end of said stem, a link pivoted to said arm, an adjustable stop on the link arranged to engage a stationary part of the machine, and 80 a spring tending to hold said stop against said part.

In testimony whereof I have signed my name to this specification.

WILLIAM C. STEWART.
